UNITED STATES PATENT OFFICE.

FREDRICK FITZ WILLIAMS, OF SALADO, TEXAS.

CHURN-POWER.

SPECIFICATION forming part of Letters Patent No. 308,722, dated December 2, 1884.

Application filed September 11, 1884. (No model.)

To all whom it may concern:

Be it known that I, FREDRICK F. WILLIAMS, of Salado, in the county of Bell and State of Texas, have invented a new and Improved Churn-Power, of which the following is a full, clear, and exact description.

The object of my invention is to provide a new and improved churn-power worked by the weight of the churn, the cream, and the churn-power.

The invention consists in the combination, with a vertically-movable carriage provided with a drum, of a rope wound on the same and having its upper end secured, from which a wheel on the carriage is operated by suitable gearing, the said wheel being connected with the dasher-staff. When the carriage descends under the action of its own weight and of the weight of the parts on it, the drum is revolved and the dasher rod or staff operated.

Reference is to be had to the accompanying drawings, forming part of this specification, in which similar letters of reference indicate corresponding parts in both the figures.

Figure 1 is a perspective view of my improved churn-power, parts being broken out. Fig. 2 is a longitudinal sectional elevation of the same.

30 A bracket-plate, A, projects from an upright, B, from which curved braces or supports C extend down to the plate A.

In the braces, supports, or side pieces, C, a drum, D, is journaled, on which a rope, E, is wound, which passes through a staple, F, on the upright B and is secured to the wall near the ceiling, or a greater or less distance from the floor and between two upright guides or track-bars, G, between which the upright B 35 is adapted to slide. The drum D is provided at one end with a squared spindle for receiving a key, H, and on the shaft of the drum a cog-wheel, J, is loosely mounted, which can be revolved from the drum by means of a ratchet and pawl. By means of suitable intermediate gearing the power is transmitted from the wheel J to a wheel, K, provided with a series of apertures, a, in one of which a hook or pin on the upper end of the dasher rod or staff L is passed; or the dasher can be con-

nected with the said wheel K, or a crank-shaft provided in place of the same by any other suitable device. The cream-receptacle M, in which the dasher works, is held on the bracket-plate A, and is held in place by an upright frame, N, on the said plate.

The operation is as follows: By revolving the drum D the rope E is wound on it, and the carriage, formed of the plate A, the upright B, and the side pieces, C, is raised with the machinery, churn, &c., on it. As the apparatus descends the wheel J is revolved by the drum, and by means of the intermediate gearing revolves the wheel K, thus reciprocating the dasher staff or rod L. The gearing is so arranged that the wheel K is revolved very rapidly for a very slight descent of the carriage. As the weight of the carriage, the machinery, the churn, and the cream all assist each other in operating the machinery the cream can be churned by a comparatively small vertical movement of the carriage.

Having thus described my invention, I claim as new and desire to secure by Letters Patent—

1. A churn-power consisting of a vertically-movable carriage provided with a drum on which a rope is wound, having its upper end fixed, and with a train of gearing for operating a churn-dasher of a churn on the carriage, substantially as herein shown and described. 75

2. In a churn-power, the combination, with the vertically-sliding carriage A B C, of the drum D, the rope E, wound on the same and having its upper end fixed, the wheel K, having apertures a, a train of gearing for operating the wheel K from the drum, the dasher-staff L, connected with the wheel K, and of the cream-vessel, substantially as herein shown and described. 85

3. The combination, with the upright guides and the carriage A B C sliding between them, of the drum D, the rope E, wound on the same and having its upper end fixed, the wheel K, a train of gearing for operating it from the drum, the dasher L, and the cream-vessel M, 95 substantially as herein shown and described.

FREDRICK FITZ WILLIAMS.
